UNITED STATES PATENT OFFICE.

MARVIN H. JESTER, OF DENVER, COLORADO.

PLASTER-BOARD-SUPPORTING METAL CLIP.

1,217,603.

Specification of Letters Patent. Patented Feb. 27, 1917.

Application filed March 16, 1915. Serial No. 14,778.

To all whom it may concern:

Be it known that I, MARVIN H. JESTER, a citizen of the United States of America, residing at the city and county of Denver and State of Colorado, have invented a new and useful Plaster-Board-Supporting Metal Clip, of which the following is a specification.

My invention relates to an improved plaster board supporting metal clip that is adapted for use with metal studding in the construction of partitions in buildings, with plastering mortars, stuccos, and other cement materials; and the objects of my invention are:

First, to provide a metal rust-proof clip that is both a right hand and a left hand clip and that can be placed instantly on a metal stud by a workman and moved quickly up and down thereon to the place desired to connect to the end or side edges of plaster boards. And

Second, to provide a simple, strong and inexpensive channel stud and plaster board securing clip that can be stamped out accurately in large numbers by dies and be shipped to all cities and towns, and that will fit commercially made sizes of channel bar studding and plaster boards and be erected by common carpenters or unskilled labor.

I attain these objects by the mechanism illustrated in the accompanying drawings, in which:

Fig. 1, is a perspective view of my improved clip.

Fig. 2, is a plan view showing an end or plan view of a channel bar and also the ends of two plaster boards in the channeled portion of the clip.

Fig. 3, is a side elevation of a channel bar showing two of my improved clips placed back to back around and on the channel bar and securing the upper edge of one plaster board and the lower edge of the other to the channel bar.

Fig. 4, is a vertical view of a channel and of my clips mounted thereon securing plaster board to one side of it.

Fig. 5, is a perspective view of a slight modification of the preferred construction shown in Figs. 1 and 2.

Fig. 6, is a perspective view of Fig. 5, showing the clip illustrated in Fig. 5 with a channeled portion on opposite sides of its body portion instead of only on one side

of it, which construction would enable plaster boards to be laid up against and be secured to both sides of the channel bar studs instead of on only one side, as shown in Fig. 4.

Fig. 7 illustrates the plaster boards laid up and secured to the channel bars with their long sides in horizontal rows and secured to break joints. And

Fig. 8, illustrates the plaster boards laid up and secured to the channel bars with their long sides extending vertically and with all boards meeting edge to edge on the channel bar.

Similar letters of reference refer to similar parts throughout the several views.

Referring to the drawings,—

The numeral 1 designates metal studding, which in plaster board partition work is placed from about eighteen inches to three feet apart along the line of a partition. I preferably use the common sizes of commercially manufactured and used channel bar.

These channel bars are secured to the floor beams or joists, and to the ceiling beams or joists by these same clips that form the subject-matter of my present invention, which are placed over the terminal ends of the channel bars and are secured to the floor and ceiling portions of rooms by nails or screws that are inserted through them as shown in Fig. 4.

My present clip is formed in suitable dies which stamp them out of thin galvanized iron of about No. 20 gage in thickness, and it comprises a flat body plate portion 3, which is cut away at one end to form an open space 4, in such a manner as to leave an outer side wall or housing 5, which has a turned-in edge 6 that acts to stiffen or truss the outer side wall, which when the clip is placed on the metal studding which may be of any form of cross section but which I preferably make of structural channel bar iron, extends around one of its ends.

There is also a stop lug portion 7 left on the body portion that holds the clip on the channel bar after it is placed in its proper plaster board receiving position on the channel bar.

This body portion 3 is made enough wider than the size of channel bar used, which is three-fourths of an inch for plastered partitions two inches thick, and one inch for plastered partitions that are two and one-

half inches wide, to enable this side wall and also another side wall 8, to be turned at right angles from it on its opposite edges.

These side wall portions 5 and 8 extend 5 at right angles to the flat body of the clip for a distance of preferably about one-half of an inch, which represent housing members that extend around the opposite edges of the channel bar studs. The channel bar 10 studs are secured in vertical positions to the floor and ceiling of a room and support sheets of plaster boards which are secured to them by my herein-described metal clip, and when done this skeleton partition 15 construction is used to form a supporting core for the plastering mortars and their finishing cements and for stucco materials.

In the construction of a partition, the 20 channel studs are placed edgewise across the thickness of the partitions to be constructed, and my improved clips are arranged and adapted to be attached to them at any part of their length by the operator almost instantly, it being necessary to simply hook 25 them around the channel bar 1, as will be presently described.

The side wall 8 forms a part of a channel shaped portion of the clip that forms a side extension of the body of the clip, and that 30 consists of this side wall 8, an end portion 9 that is bent at right angles to the side wall 8, and an outside wall member 10, that is bent at right angles to the end portion 9, which is substantially parallel to the wall 35 member 8. These three members form a channel shaped member, and it is formed flush with one end of the body portion 3, but extends a short distance beyond the ends of the stop lug 7, and of the housing side 40 wall 5. This outside channel bar housing member 5 extends from the outside side edge of the body portion 3, to preferably even with the outer end of the stop lug portion 7, and it is slightly springy or resilient under the 45 diagonal corner contact and pressure of the clip on it when the clip is forced on it, and the size of the opening between its inner edges 11 and 12 is preferably made to permit the clip to bind slightly against the 50 corners 13 and 14 of the channel bar, when the clip is placed on it, which necessitates the operator exerting a little pushing and side pressure force on the clip when placing it on the channel bar.

55 The clip preferably binds only when engaging these opposite corners of the channel bar, and the terminal ends of the inwardly projecting edge 11 and of the inner edge of the stop lug 7 are especially beveled to permit the clip to be placed partially around the channel bar before it engages its diagonally opposite corner edges, as shown in Fig. 2.

60 The channeled member of the clip is made 65 wide enough between its side walls 8 and 10

to receive loosely the ends of two abutting sheets of plaster boards, when three-quarter inch channel bars are used for studding. The plaster boards generally used are $\frac{5}{16}$ inch thick, and when 1 and $1\frac{1}{2}$ inch channel 70 bar studs are used, plaster boards varying from $\frac{3}{8}$ to a half inch in thickness are used. The clips are consequently made for the size of channel bar studs and plaster boards that are to be used in the partition. For partitions that are made of plaster blocks of about one or two inches in thickness, larger channel bar studs are used as such blocks, or used for wall construction, and will support concrete on both sides of it, and can 80 be used for the outside walls of buildings.

When the clips are placed on the channel bars, they fit and bear close against the flat solid side 17 of its recess and also close against the outer and inner edges of the 85 recess and against the edge 15 of the stop lug 7, which acts to lock the clip to the channel so that it can not come off and especially is this the case after the plaster boards are inserted in the channeled extension, which 90 holds them on the channel bar studs in a locked position. They are loose and free enough on the channel bar to be moved quickly up and down, and then they stand with their channeled extension portion 95 standing at right angles to the adjacent edge of the channel bar, in which position they are ready to receive the ends of two abutting sheets of plaster board, which are placed therein to bring their joints along 100 the center of the vertical edge of the channel bar on each alternate pair of plaster boards, while the next row of plaster boards is placed with their centers in the channel and thus alternately break joints with those that 105 meet at their ends in the channels of the clips, as shown in Fig. 7.

When the clips are in plaster board receiving position, they are locked by the shoulder 110 of the stop lug against accidental lateral or longitudinal displacement, as it is only 115 when they are moved into an angular position relative to the sides and edges of the channel bars that they can be either placed on them or removed from them, and it is 120 impossible to so twist them into that position when the plaster boards are in their channeled portions.

The operation of constructing a metal channel bar stud plaster board partition 125 with my improved metal clip is as follows:

The operator as he sets up each channel bar stud places a clip over its terminal end, with the channel groove open upward, and nails it to the floor. He then places one over the upper terminal end with its channel groove open downward, and nails it to the ceiling, the studs being cut to extend from floor to ceiling and having secured the channel bar studs at any predetermined distance 130

apart along the line of the partition, and placing them so he can break joints by placing them so that each alternate horizontal line of plaster board will extend to the centers of each alternately positioned channel bar stud, that is, in case the boards are laid lengthwise as shown in Fig. 7, but if they are laid vertically as shown in Fig. 8 they do not need a central supporting stud, unless the boards are of very large size.

The operator places the opposite edges of the plaster boards in the channels of the bottom clips until he has laid the whole first or bottom horizontal row of plaster boards, which secures the lower ends of this floor course of plaster boards to the studs, and should they not come out in even lengths at the ends, he can saw them off to fit against the studs at the walls where the partition ends, as these plaster boards saw as easily as wood.

Having laid the bottom course of plaster boards he places a clip on each stud over the one on the floor, with its channel opening downward, and slides it down over the abutting ends of the floor course of plaster boards, which secures the top ends of this floor course of plaster boards to the studs.

The operator also places a clip on the intermediate studs in the same manner, and then he has the floor row of plaster boards secured to the studs at their opposite ends and also at the centers of their lengths.

The operator then places a clip on each stud and with its channel open upward and slides it down against the top clips of the floor course so that they rest directly on top of them, as shown in Figs. 7 and 8, and those clips that are on the studs that are intermediate of the ones where the ends of boards come together receive the ends of this second horizontal course of boards, thus causing this second course to break joints with the lower course, and in this alternate break joint order he builds the boards up to the ceiling, as shown in Fig. 7.

This plaster board metal channel bar stud metal clip skeleton partition is now ready to receive on its opposite sides plastering mortars and their finishing coats, and when done if a $\frac{1}{4}$ inch channel bar stud has been used, the plastered partition will be about two inches thick and will be fire-proof, vermin-proof, and more sound-proof than a wooden stud partition.

I preferably use plaster boards measuring 16 inches wide by 30 inches long for general partition work, and my clips are arranged and adapted to rest back to back or with their plaster board receiving channel openings facing either up or down as required to secure meeting end and side edges of the boards. Each clip is consequently both a right and a left handed clip.

My present clip enables a workman to put

up these plaster board partitions without the use of nails or wedges, and while standing and working on either one side or the other as he may elect without changing from one side to the other, with great rapidity, as the 70 clip can be placed on the studs while standing and working on either side.

My improved fire-proof partition costs less than wood and takes up only from about a third to a half of the thickness in space that 75 a wooden stud partition does, and is stiffer and stronger to side-strains and pressure and to vertical compressions, and being made of galvanized iron it will not rust and corrode.

My present invention contains the channel 80 member portion of my pending application Serial No. 872,573, filed November 17, 1914, for clips for securing plaster boards to metal studding in hollow partition construction. In all other particulars of construction however, it is entirely different.

In Figs. 5 and 6 I illustrate a modification of the clip shown in Figs. 1 and 2. In these modifications the stop lug 7 and the projecting reinforcing lip 6, are not used and the 90 channel-bar occupying space is free and clear from the edge 7 throughout the length of the wall members 5 and 8, and the space between these members is preferably made so that these walls spring over the edges of the 95 channel bar with enough pressure to allow the clips to cling where placed on the channel bar, but still free enough to allow the clips to be pushed up or down on them.

In Fig. 6 a channeled portion is formed 100 on opposite sides of the body portion 3, of the clip, which allows plaster boards to be placed on and be secured to the opposite sides of the channel bars, thus forming a 105 hollow wall construction somewhat like my above mentioned pending application.

Having described my invention, what I claim as new and desire to secure by Letters Patent, is:

1. A clip comprising a metal plate member 110 provided with an open ended body portion arranged to surround a metal stud and provided with a channel groove extension portion on one side of its body portion and parallel to said side, said channel groove portion being arranged to receive and secure the corner ends and side edges of plaster boards to one side of metal studs.

2. A clip comprising a rust proof metallic plate provided with a body portion having 120 an open end portion recessed to fit around a metal stud and having one side provided with a channel groove parallel to said side and adapted to receive the edges of plaster boards and secure them to one side of said 125 stud.

3. A stud wall or partition construction clip comprising a thin metal plate having a central portion apertured to be placed partially around and locked to said metal stud 130

- against lateral or longitudinal movements, and provided with a plaster-board-receiving channeled portion at one side of and parallel to its body portion.
5. 4. In means for securing plaster boards to channel bar studding in partition construction, the combination with a stud, of a clip comprising a recessed body portion instantly attachable to any portion of the length of a 10 stud and having a laterally projecting channel member at one side of said body and channel bar inclosing portion for the reception of the edges of the plaster boards, the channel of said channel member lying parallel to said side.
15. 5. In a device of the character described, a clip comprising a body portion having a stud inclosing slot in one end thereof, and an integral portion extending from said 20 body portion and bent to form a vertically disposed channel member on one side of said stud inclosing slot for the reception of the edge portions of plaster boards, and a stop lug on said body portion arranged to lock 25 said clip to said stud against lateral and longitudinal displacement movements of said clip when properly placed on said stud.
6. In partition construction, the combination with a partition stud and plaster 30 boards, of a clip having a flat body member provided with a recess in one end and adapted to be pressed in a diagonal direction over the diagonally opposite edges of the stud and to be thus turned square 35 against one side and the opposite ends of said stud, a stop lug on one side of said body adapted to prevent accidental displacement 40 of the clip from said stud, a reinforced housing flange on the opposite side of said body portion adapted to extend past one end of said stud, and a channeled extension member on the side of said body portion from said housing flange adapted to receive 45 the ends and edges of plaster boards.
7. In partition construction, the combination with a stud, of a galvanized iron clip 50 for securing plaster boards thereto, comprising a body portion having a recess in one end permitting the clip to be pressed around said stud when held in angular relation thereto, a resilient wall or housing portion on one side of the body portion having a reinforced edge engaging a corner of said stud, the opposite side of said body portion engaging 55 another edge of said stud, said resilient wall portion being arranged to admit said clip to pass around said stud, a stop member on said body portion having a
- beveled edge to permit said clip to be pressed around said stud, a shouldered member locking said clip when applied against accidental lateral and longitudinal movements, and a channel shaped portion on the side of said body portion bearing said stop member fitting loosely over the end and side edges 60 of said plaster boards.
8. A clip comprising a rust proof metallic plate provided with a body portion having an open end portion recessed to fit around a metal stud and having each of its opposite 70 sides provided with a channel groove parallel to the side and adapted to receive the edge portions of plaster boards and secure them to the opposite sides of said stud.
9. A clip for securing plaster-boards to 75 studding, comprising a body-portion $\cap$ shaped in cross-section and having its base open at one end to receive a stud, means for preventing displacement of the clip on the stud, and a plaster-board-receiving member 80 U -shaped in cross-section and having one side in common with said body-portion.
10. A clip for securing plaster-boards to 85 studding, comprising a body-portion $\cap$ shaped in cross-section and having its base open at one end to receive a stud, an inwardly-projecting lug on the body-portion for preventing displacement of the clip on 90 said stud when applied but permitting ready attachment and disconnection of the clip during assembling and dismantling, and a plaster-board-receiving member U -shaped in cross-section and having one side in common with said body-portion.
11. A clip for securing plaster-boards to 95 studding, comprising a central portion $\cap$ shaped in cross-section and open at one end to receive a stud, and plaster-board-receiving side-members U -shaped in cross-section and each having one side in common with 100 said central portion.
12. A clip for securing plaster-boards to studding, comprising a central portion $\cap$ shaped, in cross-section and open at one end to receive a stud, means for preventing displacement of the clip on the stud, and plaster-board-receiving side-members U -shaped in cross-section and each having one side in common with 105 said central portion.
- In testimony whereof I affix my signature 110 in presence of two witnesses.
